(57) CLAIM

The ornamental design for a safety vest, as shown and described.

DESCRIPTION

FIG. 1 is a front view of a safety vest showing my new design;

FIG. 2 is a rear view of the safety vest;

FIG. 3 is a top view of the safety vest;

FIG. 4 is a bottom view of the safety vest;

FIG. 5 is a left side view of the safety vest, a right side view being identical;

6 is a top front side perspective view of the safety vest;

FIG. 7 is a top rear side perspective view of the safety vest; and,

FIG. 8 is a rear view of an embodiment of the safety vest. The broken lines in FIG. 8 are for illustrative purposes only and form no part of the claimed design.
